ROBERT B. ELROD INVENTOR.

BY

Emil F. Lange, ATTORNEY

UNITED STATES PATENT OFFICE.

ROBERT B. ELROD, OF LINCOLN, NEBRASKA.

TENT.

Application filed December 7, 1922. Serial No. 805,432.

To all whom it may concern:

Be it known that I, ROBERT B. ELROD, a citizen of the United States, residing at Lincoln, in the county of Lancaster and State of Nebraska, have invented certain new and useful Improvements in Tents, of which the following is a specification.

My invention relates to tents, and particularly the types of tents which have polygonal bases, and which have roof portions whose pitch is lower than that of the side walls of the tent.

The tent demanded by the automobile tourist must be simple in construction, light in weight, easily set up or taken down in the minimum of time, compact when folded, and rugged enough to withstand the rough usage to which it must necessarily be subjected while on camping trips. It must have few or no detachable parts which are liable to become lost or misplaced when breaking camp. The object of my invention is to provide a tent which meets these requirements.

Referring now to the drawings forming part of my application,

Figure 1 is a vertical sectional view of my tent, and showing my novel spreader in place.

Figure 2 is a plan view of my clamp and the connections between the spreader arms and the clamp.

Figure 3 is an elevation of a portion of the tent pole with my clamp secured thereto.

Figure 4 is a plan view, as viewed from above, of the jointed connection of one of the spreader arms.

Figure 5 is a side elevation of the part shown in Figure 4.

Figure 6 is a view similar to Figure 5, but with the toggle joint open instead of closed.

Figure 7 is a side elevation of the outer extremity of one of the spreader arms.

Figure 8 is an isometric view of one of the abutments secured to the tent in its corners and designed for engagement with the outer extremities of the spreader arms.

Numeral 10 refers generally to the clamp which is adapted to be secured to the tent pole. The clamp in this instance comprises four L-shaped straps 11, secured together by means of bolts or other suitable securing means 12 as shown in Figure 2. The straps

11 are secured to the tent pole 13 by means of screws 14.

The spreader arms are made up of two lengths of channel iron 15 and 16 pivotally connected at 17, with the backs of the angle iron lengths facing each other. The parts 15 and 16 are substantially equal in length. The end of the length 15 is secured to one of the ears of the clamp 10. I have here provided four spreader arms to correspond with the number of corners of the tent. The opposite end of the beam 15 is slightly upturned near the pivot 17, and has its channel walls and side wall cut away as shown in Figures 5 and 6. The upward bend in the beam 15 brings the upper channel wall of that beam immediately above the upper wall of the beam 16, where it is bent laterally at 18 and then downwardly at 19. This structure constitutes a simple and effective toggle joint and latch between two beams of channel iron.

For locking the ends of the spreader arms into the corners of the tent and in rigid relation therewith, and for preventing wear on the fabric of the tent, I provide an abutment plate as shown in Figure 8. This plate is made of sheet metal bent on its median line into the form of a right-angle.

The plate 20 is provided with apertures 21, whereby it may be secured to the tent on the inside corner. On the bottom edge of the plate 20 is an extension 20^a, this extension being closed at its lower end by a portion of the sheet metal which is bent inwardly to form a wall 20^b. The plate 20 with its parts 20^a and 20^b are integral, being preferably stamped from a sheet of cold rolled steel. The extension 20^a and the wall 20^b serve two purposes. The edges are rounded wherever they bear against the fabric of the tent, and the construction affords ample reinforcement for preventing the bending out of shape of the abutment plate.

Secured to both walls of the abutment plate is a bail 22. This bail is also preferably made out of cold rolled steel and is securely anchored at both of its ends in the plate 20. The outer end of the beam 16 is provided with a slot 23. As shown in Figure 7, the slot 23 is first parallel with the upper and lower edges of the beam, but it has an upturned portion at its inner end.

In my preferred construction, the length of the slot 23 is less than the distance between the bail 22 and the plate 20.

In use, the center pole 13 is first set up, 5 with its upper pin extending through the upper aperture in the canvas (I prefer the use of a sectional, collapsible tent pole). The spreader arms are then unfolded and they are brought into position to register 10 with the corners of the tent. The outer ends of the spreader arms with their apertures 23 are then brought to bear against the bails 22, after which a slight downward pull on the spreader arms at their joints will cause 15 the toggle connections to latch. This causes the tent to be stretched taut at all points in the roof portion, and at the same time the strain is so evenly distributed that there is no danger of tearing or otherwise injur- 20 ing the fabric. The ends of the spreader arms do not bear against the canvas nor even against the plates 20, but they have rather a rocking engagement with the plates through the bails 22. This relation 25 of parts not only protects the fabric when setting up the tent, but it also relieves the tent from excessive wind strains. When folded, the bundle is very compact. The pole is preferably sectional with the sections of approximately the length of the beams 15 or 16. The time consumed in setting up or in taking down the tent is reduced to the minimum because of the simplicity of construction and the small number of parts.

I have shown and described a tent having four sides. It is of course possible by slight modification of the structure to apply the same principle to a polygonal tent having any other number of sides than four, and I wish it understood that I do not relinquish any of my rights to any of the equivalents of the structures which I have shown and described.

Having fully described my invention, and its uses and advantages, what I believe to be new and desire to secure by Letters Patent of the United States is:—

1. In a tent having a single centrally-positioned tent pole, a clamp adapted to be secured to the tent pole, said clamp consisting of a plurality of L-shaped straps

each having a long and a short leg with the short leg of one strap bearing against the long leg of the adjacent strap to form ears 55 at the corners of the clamp, connections between adjacent straps through the ears, jointed arms pivotally connected to said ears, and means at the extremities of said jointed arms for engaging the tent at the 60 corners formed by the junction of the walls and the roof of the tent.

2. In a tent having a single centrally-positioned tent pole, spreader arms pivotally secured to the tent pole, said spreader arms comprising each two channel iron beams pivotally connected at their inner extremities, a tongue projecting from the upper edge at the inner extremity of one of the channel iron beams and over the upper 70 edge of the other of said channel iron beams to constitute a toggle latch for said pivotally connected channel iron beams, bails anchored in the walls of the tent at the corners thereof, and means at the outer extremities of said spreader arms for engaging 75 said bails.

3. In a tent having a single centrally-positioned tent pole, plates secured to the fabric of the tent in the corners thereof, 80 bails secured to said plates, said bails extending transversely across the vertical corners of the tent, spreader arms pivotally secured to the tent pole, and means at the outer extremities of said spreader arms for 85 engaging said bails.

4. A tent having means for spreading the walls at the upper portion of the tent, said means comprising plates secured to the walls of the tent, bails projecting from said 90 plates, spreader arms extending from side to side of the tent, said spreader arms having notches, said notches being curved upwardly at their inner ends and having their openings at the outer extremities of said 95 spreader arms, the arrangement being such that when the tent is set up with the notches of the spreader arms engaging the bails the connection will permit limited rocking movement between the spreader arms and 100 the walls of the tent.

In testimony whereof I affix my signature.

ROBERT B. ELROD.
